UNITED STATES PATENT OFFICE.

FREDERICK B. MILES, OF PHILADELPHIA, PENNSYLVANIA.

VERTICAL PLANER.

SPECIFICATION forming part of Letters Patent No. 601,580, dated March 29, 1898.

Application filed May 9, 1896. Serial No. 590,900. (No model.)

To all whom it may concern:

Be it known that I, FREDERICK B. MILES, a citizen of the United States, residing in Philadelphia, Pennsylvania, have invented certain 5 Improvements in Vertical Planers, of which the following is a specification.

The main object of my invention is to construct a vertical planing-machine in such a manner that it will either plane in a vertical 10 path or in a horizontal path by simply changing the feed mechanism, as fully described hereinafter.

My invention further relates to details of construction fully described hereinafter.

15 Referring to the accompanying drawings, Figure 1 is a face view of my improved machine. Fig. 2 is an end view looking in the direction of the arrow, Fig. 1. Fig. 3 is a plan view. Fig. 4 is an enlarged plan view of one 20 portion of the machine. Fig. 5 is a section on the line 5 5, Fig. 4. Fig. 6 is a view looking in the direction of the arrow, Fig. 4. Fig. 7 is a sectional view on the line 7 7, Fig. 8, of the tool-carrier. Fig. 8 is a side view of the 25 tool-carrier. Fig. 9 is an end view of the tool-head.

A is the bed of the machine. At one side of this bed is the table A', having grooves. On this table is clamped the work to be planed. 30 Projecting upward from the base A is the frame A², on which are the longitudinal slide-ways a a for the carriage B, Fig. 1. This frame is braced at the back by piers A³, as shown in Fig. 3.

35 The carriage B has slides adapted to the ways a a of the usual form, being simply undercut, so as to hold the carriage in position. In the ways a a are longitudinal screws c c, adapted to a bearing a' at each end of the 40 frame A², and these screws are geared to a vertical shaft C by bevel-gearing c', so that when the shaft C is turned the screws c will turn in unison. The screws c c are adapted to nuts on the carriage, so that when the 45 screws are turned the carriage will travel across the face of the frame A².

The carriage B extends a considerable distance above the frame A², as shown in Fig. 1, and adapted to this carriage is a vertical screw 50 e, mounted in bearings b b on the carriage, and this screw is driven through the bevel-gears e' by a splined shaft E, adapted to bear-

ings in the base of the machine. Adapted to a vertical slideway b' is a tool-carriage D. This tool-carriage has a nut with which the 55 screw e engages, so that when the screw is turned the tool-carriage will be moved in a vertical line.

The shafts C and E are so geared to the mechanism for feeding and traversing the tool 60 that when it is wished to plane in a vertical line the traverse mechanism is geared to the shaft E and the feed mechanism is geared to the shaft C; but when it is desired to plane in a horizontal line the clutch mechanism is 65 shifted so that the shaft E becomes a feed-shaft and the shaft C a traverse shaft. The mechanism is readily changeable at a moment's notice.

Connected to the tool-carriage D are cords 70 or chains b², which pass over sheaves b³ on the carriage B and are attached to a counterbalance-weight b⁴ within the frame of the carriage B, as shown in Fig. 3.

F is a belt-shifter rod adapted to bearings 75 f f on the frame A² and situated in the present instance directly under the lower slide-ways a. On this belt-shifter rod is a lever f', Figs. 4 and 5, which is connected to a two-armed lever F' by a rod f². This lever F' is 80 pivoted at f³ to a bracket on the frame of the machine. The lever f² is slotted longitudinally, and adapted to the slot is a pivot-block f⁶, which can be adjusted and locked in any position on the lever. The rod f² is pivoted 85 to the block, as shown in Fig. 4. One arm of the lever F' is connected to a belt-shifter F² by a rod f⁴. This belt-shifter is of the ordinary construction and is adapted to shift two belts in one operation.

90 The driving-pulley on a shaft G, adapted to bearings on the frame of the machine, is made in the present instance with two faces g' g², one less in diameter than the other, and on each side of the pulley G are the loose pulleys g³ and g⁴.

95 The belt-shifter is so arranged that either one or the other of the belts can be shifted from its loose pulley to the fast pulley without disturbing the other belt, as will be readily 100 seen by referring to Fig. 4 of the drawings.

On the belt-shifter rod F are two adjustable sleeves f⁵, having friction-rollers projecting in the path of two cam-faced shifters

b⁵ on the carriage B. One shifter is at the front of the carriage and the other at the back, so that when the carriage has reached the limit of the forward movement the shifter 5 *b⁵* strikes the roller on the sleeve secured to the shifter-rod and turns the rod in its bearings sufficiently to operate the belt-shifter F², so that the direction of rotation of the screws *c c* will be reversed and the carriage passed 10 in the opposite direction. The same operation is repeated when the carriage reaches the limit of its return stroke. The belts pass from the pulleys on the counter-shaft G' to the pulleys on the shaft G, Fig. 2, and it will 15 be noticed that the pulleys are of different diameters, so as to provide for a slow forward feed and a quick return.

When the carriage B is fed to move the tool to a new path, then the sleeve *f⁵* of the shifter-rod F is moved, so as to be clear of the shifter-cams on the carriage B, and the carriage D then becomes the shifter. To accomplish this, I mount on projections of the carriage B levers *h*, which carry the shifter-rod H, and this shifter-rod is connected at its lower end to a lever *h'*, splined to the shifter-rod F, so that while the lever will turn the shifter-rod F it will slide upon it with the carriage. This shifter-rod H is counterbalanced 20 by the weights *h²* of the levers *h*. Extending throughout the length of the rod is an undercut groove, to which are adapted the blocks *h³*. These blocks are adjusted according to the work to be planed, so that the carriage B will strike the upper block in its upward movement and shift the belts through the rods H and F and belt-shifter F², and when the carriage reaches its lowest position 25 it will strike the lower block and again shift the belt.

Referring now to Figs. 4, 5, and 6, in the bed of the machine is a shaft I, geared to the shaft G through bevel-gears *i i'* *i²*. The bevel-gears *i i'* are splined to the shaft G and are 30 adapted to be moved into and out of gear with the bevel-wheel *i* by means of a lever I', which carries a segmental shoe *i³*, adapted to a groove in the hub of the bevel-wheels *i i'*.

The lever I' is a handle-lever and has a pin 35 *i⁴*, adapted to openings in a fixed segment I², so that it can be adjusted and locked with either of the bevel-pinions *i i'* in gear with wheels *i* or locked out of gear.

As shown in the drawings, the lever I' is 40 connected by a rod *i⁵* to the pivot *f⁶* of the rod *f²*, which slides in ways in the face of the lever F', so that when it is wished to cut on the ordinary return stroke it will shift automatically, so that the advantage of the slow feed 45 and quick return is gained and the machine is adapted to cut in either direction at the proper speed with quick return.

Adapted to a bearing *a²* in the base A is 50 mounted a bevel-pinion J, and in a bearing *a³* is mounted a bevel-pinion J'. These pinions are shouldered, so that they will not move longitudinally in their bearings. Each pinion

has two clutch-faces, one at the forward end and one at the back. Adapted to engage with the forward clutch-face of the pinion J is a 70 clutch K, mounted on the shaft I, and adapted to engage with the forward clutch-face of the pinion J' is a clutch K'. Also on the shaft I and mounted between the two pinions is a clutch K², having two clutch-faces, one adapted to engage with the rear clutch-face of one pinion J and the other clutch-face adapted to engage with the face of the other pinion J'. This clutch K² has gear-teeth *k* on its periphery meshing with the teeth of a wheel L, 80 mounted on a stud L', carried by a bracket a⁴. The shaft I is hollow for a certain distance, and mounted in this shaft is a shifter-rod K³, which is connected to the several clutches K K' K², the clutches K' K² being connected to 85 the rod by pins which pass through elongated slots in the shaft I.

The hub of the clutch K is mounted between the head *k'* of the rod and a collar, so that there is a certain amount of lost motion 90 in the movement of the rod before this clutch is acted upon. A spring is mounted in the head *k'* of the rod, so that the lever can be shifted, and the clutches will go into place as the teeth come in line.

The head of the rod K³ is connected to a handled shifting lever K⁴, which can be locked in any position by a lever engaging the notches of a segment *k²*, mounted in a standard *k³*, secured to the base of the machine.

The clutch K² is loose on the shaft I, so that the motion of the shaft is not imparted to this clutch, but is simply imparted to the clutches K and K', the clutch K² being driven by the tool-feeding mechanism M through the wheel L, the shaft I being the medium through which the traversed motion is given to the slide or tool-carriage, so that it will be seen that when the lever K⁴ is in the mid-position, Fig. 5, all the clutches are out of gear and the mechanism is at a standstill; but when the lever is shifted in the direction of the arrow, Fig. 5, it throws the clutch K' into gear with the pinion J' and the clutch K² into gear with the pinion J, and as the pinion J' meshes 105 with a bevel-wheel *j'* on the shaft C and the pinion J meshes with a wheel *j* on the shaft E the slow feed motion is imparted to the shaft E and the traverse motion imparted to the shaft C, the clutch K being out of gear; 110 but when the lever is shifted in the opposite direction the clutch K' is thrown out of gear, while the clutch K is thrown into gear with the pinion J and the clutch K² thrown into gear with the pinion J', so that the slow feed 115 motion is imparted to the shaft C and the traverse motion is imparted to the shaft E.

The traverse motion M shown, Fig. 4, has 120 been used by me for feeding ordinary planers, &c., the shaft M' being geared to the shaft G through this motion, as clearly shown in Fig. 4. On the end of the shaft M' is a slotted arm M², and adapted to this arm is a head *m*, which 125 can be adjusted in the slot by a screw *m'*, so

as to alter the distance between the pivot-pin on the head and the center of the shaft. This head is connected by a rod m^2 to an arm L^2 , mounted in the present instance on the hub of the wheel L . Carried by this arm is a spring-pawl l , which engages with the ratchet-teeth on the rim of the wheel L , so that as the feed mechanism revolves the shaft M^2 the arm L^2 moves the wheel L forward a certain number of teeth and returns as the shaft M^2 continues its motion. Thus it will be seen that the feed of the tool can be regulated by adjusting the head m on the arm M^2 .

When it is required to move the feeding mechanism by hand, a handle is placed on the shaft L^3 , which has a pinion l' gearing with the wheel L , so that by turning this shaft L^3 the tool can be readily adjusted.

On the tool-carriage D , Figs. 7, 8, and 9, is a tool-slide D' , adapted to be adjusted in ways by a feed-screw p . Mounted in the cylindrical socket of this tool-slide is the shank D^3 of a head D^2 . The shank D^3 is held in the adjusted position by the clamp-bolts d . A collar d' can also be used if necessary. The shank is made cylindrical, so that the tool can be adjusted to cut in either of four positions, according to the character of the work, and the head can be moved out to reach places ordinarily inaccessible.

In the head D^2 is a circular opening having undercut edges, and secured to the head is a semicircular flange d^2 , held in position by screws d^3 , and confined in this circular opening is the circular base d^4 of the tool-head D^4 . Carried by the tool-head is a tool-carrier D^5 , adjustable on the tool-head by means of the screw d^5 . The carrier has the usual tool-posts d^6 , by which the tool is fastened to the head.

By the above arrangement the tool can be universally adjusted on the carriage D .

The feed-screw p is geared to a shaft p^3 by bevel-gears p^1 p^2 , and on the shaft p^3 is a ratchet-lever p^4 , having an arm p^5 , connected by a rod q to a feed-lever Q , which is slotted, and adapted to the slot is a block q' , so that by adjusting the block in the slot the feed can be increased or diminished in either direction. The lever Q has an arm q^2 , connected by a rod q^3 to a lever Q' , pivoted to the frame of the machine at q^4 , and on this lever are two rollers which are arranged on each side of the bar H , so that when the bar is moved it will feed the screw a certain distance. The screw can be operated by hand by reciprocating the handle p^5 .

It will be seen by the above description that the machine as described makes it possible to either plane from the right or the left with a slow forward traverse and a quick return, or from the bottom to the top or from the top to the bottom with a slow forward traverse and a quick return.

I claim as my invention—

1. The combination of the base A , the frame A^2 , guides on said frame, screw-shafts mounted in said frame, a vertical shaft C geared to

said screw-shafts, a carriage B adapted to the ways on the frame A^2 , and controlled by the said screw-shafts, a vertical screw mounted 70 on the said carriage, a longitudinal shaft E geared to the vertical screw-shaft, a tool-carrier D mounted on the carriage B and controlled by the said longitudinal screw-shaft E , traverse mechanism, a shaft I geared to 75 said traverse mechanism, feeding mechanism, a clutch K^2 geared to said feeding mechanism, said shaft I having clutches, pinions J J' geared respectively with the shaft E and the shaft C and operating mechanism for the 80 clutches so that when the shaft I is thrown in gear with the pinion J the clutch K^2 is thrown in gear with the pinion J' and when the shaft is thrown in gear with the pinion J' the clutch K^2 is thrown in gear with the pinion J , substantially as described. 85

2. The combination in a vertical planer, of the frame, the carriage, a tool-carrier D movable on said frame, a tool-slide on the carrier, said slide having a horizontal socket, a 90 head D^2 having a shank, the said shank being mounted in the socket, means for clamping the shank in the socket and a tool-post on the head, substantially as described.

3. The combination in a vertical planer, of 95 the carriage, a tool-carrier thereon, a feed-screw for the carrier, a ratchet-lever geared to the said feed-screw, a shifter-bar H capable of vertical and lateral movement and adjustment, said ratchet-lever being connected 100 to the bar H in such a manner that when the bar H is moved it will turn the feed-screw, substantially as described.

4. The combination in a vertical planer, of 105 the frame, a carriage B , a tool-carriage D , tool-slide D' adapted to ways on the carrier, a head D^2 having a shank adapted to the slide and having an undercut circular opening, a tool-head D^4 having a circular base adapted to the said opening, and means for locking the tool-head in an adjusted position, substantially as 110 described.

5. The combination in a vertical planer, of 115 the frame, a carriage B , a tool-carrier D , tool-slide D' adapted to ways on the carrier, a head D^2 having a shank adapted to the slide and having an undercut circular opening, a tool-head D^4 having a circular base adapted to the said opening, and means for locking the tool-head in an adjusted position, and a tool-carrier D^5 adjustably mounted on the tool-head, substantially as described. 120

6. The combination in a tool-carriage, its 125 slide, a tool-head having a shank adapted to the slide, and having a circular undercut opening, a semicircular flange d^2 , means for holding the flange in position and a tool-head having a circular base adapted to the said opening in the flange d^2 , substantially as described. 130

7. The combination in a planing-machine, of a vertical bed, guides thereon, a carriage adapted to said guides, a tool-carrier on the carriage adapted to travel vertically thereon,

means for driving the carriage horizontally, and means for driving the tool-carrier vertically, means for imparting to the driving mechanism of the carriage a slow traverse motion and quick return, and to the driving mechanism of the tool-carrier a slow feed motion and means for shifting said means to impart to the driving mechanism of the carriage a slow feed motion, and to the driving mechanism of the tool-carrier a slow traverse motion and a quick return, so that the work can be planed from the right to the

left or from the left to the right with slow traverse and quick return, or can be planed from the bottom up or from the top down with a slow traverse and quick return, substantially as described.

In testimony whereof I have signed my name to this specification in the presence of two subscribing witnesses.

FREDERICK B. MILES.
